UNITED STATES PATENT OFFICE

168,306

GLASS TOP COFFEE TABLE

Stanley Lee, St. Charles, Ill.

Application March 22, 1952, Serial No. 19,010

Term of patent 3½ years

(Cl. D33—14)

To all whom it may concern:

Be it known that I, Stanley Lee, a citizen of the United States and a resident of the city of St. Charles, in the county of Kane and State of Illinois, have invented a new, original, and ornamental Design for a Glass Top Coffee Table, of which the following is a specification, reference being had to the accompanying drawings, forming part thereof.

Figure 1 is a front elevational view of a glass top coffee table, showing my new design;

Figure 2 is a side elevational view thereof as seen from the right, only one side being shown as both sides are alike;

Figure 3 is a top plan view of the table; and,

Figure 4 is an enlarged vertical cross-sectional view thereof, taken along a plane located intermediate the sides, as seen when viewed from the right.

I claim:

The ornamental design for a glass top coffee table, as shown and described.

STANLEY LEE.
